UNITED STATES PATENT OFFICE.

CARROL R. WOOTEN, OF DALLAS, TEXAS, ASSIGNOR TO DAYLITE LENS COMPANY, A COPARTNERSHIP COMPOSED OF ALBERT E. DOSS, CARROL R. WOOTEN, AND EUGENE A. OGLETREE, OF DALLAS, TEXAS.

DESIGN FOR A LENS FOR HEADLIGHTS.

57,757.

Specification for Design.

Patented Apr. 26, 1921.

Application filed December 22, 1919. Serial No. 346,799. Term of patent 3½ years.

To all whom it may concern:

Be it known that I, CARROL R. WOOTEN, a citizen of the United States, residing at Dallas, in the county of Dallas and State of Texas, have invented a new, original, and ornamental Design for a Lens for Headlights, of which the following is a specification, reference being had to the accompanying drawing, forming part thereof.

The figure is a front view of a lens for headlights showing my design.

I claim:

The ornamental design for a lens for headlights as shown.

CARROL R. WOOTEN.
